WORK GUIDING MEANS FOR SHOE
SEWING MACHINESFred Ashworth, Wenham, Mass., assignor to
United Shoe Machinery Corporation, Flemington, N.J., a corporation of New Jersey

Application September 12, 1945, Serial No. 615,725

12 Claims. (Cl. 112—51)

1

The present invention relates to work guiding means for machines constructed to sew the outsole to the welted upper and insole of a lasted Goodyear welt shoe, and more particularly to improvements in sewing machines such as that disclosed in United States Letters Patent No. 2,296,888, granted September 29, 1942, on an application filed in the name of Carl F. Whitaker, having a sole edge gage and crease guide arranged to prevent the inseam of a Goodyear welt shoe from being cut by the stitch forming devices during the insertion of the outseam.

The objects of the present invention are generally similar to those of the patent referred to, in which cutting or other damage to the inseam along the shank portion of a shoe is prevented when sewing the outsole to the welt of the shoe as the shoe is tipped about the point of operation of the machine, except that the purposes of the present invention are not only to prevent cutting the inseam along the forepart and shank portions of the shoe, as in the patented machine, but also to insure and facilitate proper insertion of the outseam along the sides of the heel seat portion of the shoe along which the projecting marginal portions of the outsole and welt are relatively narrow and the crevice between the upper and the welt is extremely shallow so that the shoe must be urged with a heavier pressure and greater precautions are required than while sewing either shank or forepart portions of the shoe.

A further object of the invention is to provide in an outsole shoe sewing machine a novel and improved guide conveniently shiftable to any of three positions to facilitate sewing along different marginal portions of a shoe, particularly along the heel seat as well as the shank and forepart portions and to insure accurate movement of the guide to any of these positions through simply performed and effective adjustments during operation of the machine.

In the machine of the Whitaker patent, the edge gage and crease guide are adjustable during sewing operations to insure location of the marginal portions of the shoe in either of two positions, one of which is effective in guiding the shoe properly along the forepart, and the other along the shank of the shoe to prevent cutting the inseam. It has been found desirable in many instances to start an outseam somewhat ahead of the shank portion of the shoe and to insert stitches overlapping the heel seat portion. As illustrated herein, the outseam connecting the welted upper and outsole does extend to this portion of the shoe.

2

A common practice is to trim off the projecting margin of the sole edge after sewing along the heel seat portion to such an extent as to provide no substantial extension beyond the bulging upper. The outseam is therefore inserted as far as possible within the crease between the extension and upper to avoid cutting the stitches while trimming. Accordingly, it is essential to avoid any possibility of restricting the extent to which the shoe may be forced against the work support of the machine on which the outseam is sewed to insure insertion of stitches deeply within the crease along this portion of the shoe. For this purpose, it is desirable to shift the sole edge gage to an extreme rearward position entirely out of reach or possible engagement with the sole edge. If a movable crease guide is employed as in the patented machine, this too must be shifted rearwardly. When the shank of the shoe is reached, with the inseam connecting the welt to the upper and insole, the edge gage or other guiding means should, for best results, be moved to an intermediate position to protect the inseam from contact with the sewing instrumentalities and, along the forepart, the edge gage should be shifted to a third position to secure a uniform guiding action with the shoe presented to the machine in a substantially flat untilted position. To insure proper shifting movement of a shoe guiding edge gage positively and accurately in these three positions during sewing operations, it is necessary to provide in addition to the usual manually operable adjusting arm a suitable third position shifting means, both of which may be actuated by easily accomplished manipulations on the part of the operator without complicated and time-consuming efforts.

In accordance with these objects of the invention, one feature resides in an outsole shoe sewing machine having an adjustable edge gage and a manually operable regulating arm mounted for limited movement to shift the edge gage during sewing operations to either of two positions determined by the limits of movement of the arm, in which there is provided means actuatable during sewing operations to shift the edge gage to a third position. In the illustrated form of this feature, the third position shifting means is mounted on the manually operable edge gage regulating arm so that the attention of the operator need not be diverted from the regulating arm which is customarily employed for edge gage adjusting purposes while shifting the edge gage toward and from its several positions.

Preferably, locking means also is provided for preventing movement of the third position shifting means except in one position of the regulating arm. With such arrangement, it will be possible to shift the edge gage only through a definite sequential movement. In this way, shifting movement of the edge gage will be limited to three positions, and combined movements of the arm and third position shifting means will confine the movements of the edge gage accordingly. Another purpose of the locking means is to prevent continuous movement of the edge gage from one extreme adjusted position to the other extreme position in the opposite direction without stopping in an intermediate position.

These and other objects and features of the invention will become apparent from a consideration of the following description and the appended claims taken in connection with the accompanying drawings, in which

Fig. 1 is a view in right-hand-side elevation of a portion of a shoe outsole sewing machine having an edge gage actuating mechanism embodying the features of the present invention;

Fig. 2 is a detailed view, on an enlarged scale, of the edge gage adjusting segment of the machine illustrated in Fig. 1;

Fig. 3 is a similar detailed view of one of the connections for actuating the segment in Fig. 2;

Fig. 4 is a bottom plan view of a Goodyear welt shoe, indicating the positions of the inseam with relation to the outseam when the outseam is inserted on the machine of the present invention;

Fig. 5 is a sectional view, on an enlarged scale, at the heel seat of the shoe illustrated in Fig. 4, taken along the line V—V of Fig. 4 during sewing operations;

Figs. 6 and 7 are similar sectional views taken at the shank and forepart along the lines VI—VI and VII—VII, respectively, of Fig. 4 during sewing operations;

Fig. 8 is a view in front elevation of the edge gage and adjusting mechanism of the machine;

Fig. 9 is a plan view, partly in section, of the mechanism illustrated in Fig. 8 showing the positions of the parts when the edge gage is moved to extreme retracted position to enable sewing along the heel seat of a shoe, as in Fig. 5;

Fig. 10 is a plan view, on an enlarged scale, of a portion of the connections in the mechanism of Fig. 9;

Fig. 11 is a sectional view of the parts illustrated in Fig. 10, taken along the line XI—XI;

Fig. 12 is a plan view, on a reduced scale, of the edge gage adjusting mechanism, illustrating the positions of the parts assumed while the edge gage is adjusted to an intermediate position for sewing along the shank of a shoe, as in Fig. 6;

Fig. 13 is a similar plan view, on an enlarged scale, with the parts in the same positions and with the adjusting segment broken away and shown in section to disclose the underlying construction;

Fig. 14 is a similar view of the same parts in the same positions as seen along the line XIV—XIV of Fig. 11;

Fig. 15 is a plan view, on a reduced scale, of the edge gage adjusting mechanism, illustrating the positions of the parts while the edge gage is shifted to its foremost position for sewing along the forepart of the shoe, as in Fig. 7;

Fig. 16 is a similar view, on an enlarged scale, of the same parts in the same position, with the adjusting segment broken away and shown in

section similar to that of Fig. 13 to disclose the operating connections;

Fig. 17 is a similar view of the connections in the same positions indicated in Fig. 16 as viewed along the line XIV—XIV of Fig. 11;

Fig. 18 is a plan view of a modified form of edge gage and adjusting mechanism operating in a manner similar to that illustrated in Figs. 1 to 17, inclusive, indicating the positions of the parts while the edge gage is in a fully retracted position for sewing along the heel seat of a shoe, as in Fig. 5;

Fig. 19 is a plan view of the same mechanism, indicating the positions of the parts with the edge gage in an intermediate position for sewing along the shank of the shoe, as in Fig. 6; and

Fig. 20 is a similar view of the same parts, some of which are broken away and illustrated in section, taken while the edge gage is in its foremost position for sewing along the forepart of the shoe, as in Fig. 7.

The machine of the drawings is intended to sew together the marginal portions of an outsole and a welt of a Goodyear welt shoe with a seam extending from the heel seat at one side, along the shank to the forepart and then at the other side of the shoe returning to the heel seat. In sewing an outseam, it is necessary to maintain the projecting marginal portions of the shoe parts operated upon in proper relationship to the stitch forming devices of the machine and, in so doing, frequent difficulty is encountered, according to common shoe practices, in maintaining the outseam clear of the inseam which connects the welt to the upper and insole of the shoe.

In Fig. 4, the outsole of a Goodyear welt shoe is illustrated at 22 having a partially completed outseam 24 connecting the outsole with a welt 26 (see Figs. 5, 6 and 7). The welt 26 is connected to a shoe upper 28 and an insole 30 by an inseam 32, represented in plan in Fig. 4. In sewing the outseam, it is common practice to employ an edge gage to determine the location of the outseam about the forepart of the shoe and to retract the edge gage from engagement with the shoe sole while sewing along the shank, to enable the shoe to be pressed against the machine and tilted sufficiently for proper insertion of stitches at a suitable distance from the extreme edges of the outsole and welt. In pressing the shoe against the machine along the shank and heel seat, the upper engages the outer inclined surface of a work support 34, the shoe being tilted to enable the work support to enter the crease formed by the projecting marginal portions of the welt and the surface of the upper which is stretched about a last 36. As in all machines of this nature, the projecting marginal portions of the welt and outsole are clamped during stitch formation against the work support by a presser foot 35.

Along the forepart of the shoe, the last contour swings away abruptly from the welt so that the work support may enter the crease readily without tilting the shoe, the shoe being easily guided by a sole edge gage. Along the shank, however, the contour of the last is such that the crease forms a relatively acute angle with the upper engaging the lower edge of the work support and tending to hold the shoe away from the sewing point in the machine. To offset this tendency, it is a practice to retract the edge gage and to tilt the shoe as indicated in Fig. 6. In so doing, a new difficulty is presented by a danger of intersecting the threads in the inseam by the outsole stitch forming devices, frequently to such an ex-

tent as to sever the inseam threads or seriously weaken them. For this reason, an adjustable crease guide, provided in the machine of the Whitaker patent above referred to, is shifted to hold the inseam clear of the stitch forming devices while sewing the outseam 24 along the shank of the shoe. The mechanism for shifting the crease guide and for retracting the edge gage while sewing along the forepart is comparatively simple and direct acting, a regulating handle being provided which is movable manually to either of two positions. The two positions of the handle in the Whitaker machine are determined by limiting stops provided in the machine so that a simple operation only is required to shift the crease guide and adjust the edge gage alternatively to either of two corresponding operative positions.

In most types of outseam work, it has been found desirable to sew the outseam not only about the forepart of a shoe and along the shank but also to begin the sewing operations from a point overlapping the heel seat ahead of the extreme end of the inseam, as indicated in Fig. 4. The outseam is then continued entirely around the shoe to a point overlapping the heel seat beyond the end of the inseam on the other side, the boundary of the heel seat being to the right of the line V—V. With a shiftable crease guide, such as that employed in the Whitaker machine, provision is made for changing the position of the crease guide and edge gage together in such a way that, when the crease guide is moved out of operative position, the edge gage moves into operative position, and vice versa. In order to sew any portion of the heel seat in a shoe, it has been found necessary to insert the outseam without restriction from either an edge gage or a crease guide. Thus the alternatively acting adjusting mechanism of the Whitaker machine does not provide the proper conditions for sewing an outseam in this way, either the edge gage or the crease guide acting at all times. Whatever the guiding member, therefore, the present invention contemplates shifting it selectively into any of three predetermined positions to enable the heel seat to be sewed, rather than two as with the Whitaker mechanism. In accomplishing this result, it is necessary to provide an adjusting mechanism by means of which a shift may be made instantly without special precautions or attention on the part of the operator. Otherwise, the adjustment will become so burdensome as to more than offset the benefits obtained in eliminating damage to the inseam and in insuring proper insertion of stitches along the heel seat portion of the shoe.

The actuating mechanism for the guiding means of the present invention, accordingly, comprises simply actuated and accurately controlled connections for adjusting an edge gage, indicated at 38, to any one of three positions at the will of the operator. The edge gage, when actuated by the said mechanism, will be entirely disengaged from the marginal portions of the outsole and welt along the heel seat portion of the shoe as indicated in Fig. 5, so that the stitches will be inserted as far as possible from the extreme edges of the outsole and welt where there will be no opportunity of damage to the outseam even when the outsole is trimmed unusually close to the upper. The edge gage also may be shifted to an intermediate position where the outsole and welt may be guided properly to prevent the stitches of the inseam from being intersected by

the outseam stitch forming devices, as in Fig. 6, and to an extreme forward position for guiding the outseam along the forepart of the shoe, as in Fig. 7, for the usual forepart sewing operations.

5 The mechanism for regulating the edge gage in this way includes a manually operable handle 39 formed at the end of an arm 40, and a second manually operative handle provided by an arm 42 mounted on but movable relatively to the arm 10 40 about a pivot consisting of a rod 44 bent at its upper end to serve as a guard. When the arm 40 is moved as far as possible in either direction, it adjusts the edge gage between the intermediate position of Fig. 6 and the extreme forward position of Fig. 7. When the second arm 15 42 is moved, it shifts the edge gage between the intermediate position of Fig. 6 and the extreme rearward retracted position of Fig. 5 beyond that determined by the limits of movement of the arm 20 40, the arm 40 remaining stationary. Locking means also is provided to prevent operation of the arm 40 when the edge gage is shifted to extreme retracted position of Fig. 5 and to prevent movement of the arm 42 when the edge gage is 25 adjusted to its extreme forward position of Fig. 7.

The connections for adjusting the edge gage between the extreme forward position of Fig. 7 and the intermediate position of Fig. 6 are similar to those illustrated in the Whitaker patent and 30 include a carrier 46 pivoted at its lower end on a fixed stud 48 and retained by a spring 50 in contact with a cam 52 engaging the upper end of the gage. The cam 52 is secured to a vertical shaft 54 having at its lower end a pinion 56 meshing with a segment 58 fixedly connected with the upper end of an adjusting shaft 60 to the lower end of which the arm 40 is pinned.

The adjusting arm 40 is capable of limited movement with the adjusting shaft 60. To limit 40 the rearward movement of the arm 40 while adjusting the edge gage forwardly, the arm has projecting from its hub a lug arranged to contact with a setscrew 62 threaded into a projecting portion of the machine frame from a bearing 45 for the shaft 60. The forward movement of the arm 40 also is limited. The upper end of the adjusting shaft has secured to it a plate-like connecting member 64 (see Fig. 3) having a cam slot 66 at one side of the shaft 60 within which 50 is disposed a pin 68 passing through an L-shaped slot 70 in and adjacent fixed projecting portion of the machine frame. When the arm 40 is moved forwardly, the slotted portion of the member 64 and the pin 68 are moved rearwardly of 55 the machine until the pin engages the angle of the slot 70 where further movement of the member and arm is arrested.

As in the prior machines, the handle of the 60 adjusting arm 42 is moved by the operator through a single rapid manipulation between the limits of its movement to change the position of the edge gage, the movement limiting means being depended upon to secure the proper adjusted 65 position without the exercise of special attention upon the part of the operator. To retain the adjusting arm and shaft in position after being moved, the bearing for the shaft 60 is slotted at 70 72 and is adjustably contracted along the slotted portion against the shaft by a clamp screw 74 passing through an enlargement in the slotted portion of the bearing to impart a frictional resistance against rotating the shaft.

To shift the edge gage between its intermediate 75 position of Fig. 6 to its extreme rearward re-

tracted position of Fig. 5, the shifting arm 42 which moves with the adjusting arm 40 is operated still further in a forward direction without corresponding movement of the adjusting arm 40. The shifting arm 42, therefore, swings on its pivot 44, causing a rearward projecting portion of the shifting arm 42 connected through a link 76 to a slide 78 to be moved to the right. The slide 78 passes radially through an enlarged perforated portion of the shaft 60 and supports at its extreme left end the pin 68 in vertical position while permitting the pin to slide horizontally. To guide the pin in vertical position, the left end of the slide 78 has a rectangular head 80 embraced loosely between a pair of parallel arms 82 extending from the enlarged portion of the shaft 60. When the slide 78 is moved from left to right, the lower end of the pin 68 moves along a radial portion of the slot 70. During this movement, the upper end of the pin 68 moves along the slot 66 in the member 64 which has a short portion substantially parallel with the radial portion of the slot 70 and an inclined portion which causes movement of the member 64 relatively to the machine frame in which the slot 70 is formed. This relative movement of the member 64 causes the segment 58 which is adjustably clamped thereto by an eccentric bushing and clamp screw device 71 to be moved to a third position and the edge gage to be shifted to its extreme retracted position of Fig. 5, the movement of the slide 78 and the arm 42 being limited by the ends of the slot 66 and of the radial portion of slot 70.

To shift the edge gage forwardly from its extreme retracted position of Fig. 5 to its intermediate position of Fig. 6, the arm 42 is moved rearwardly about its pivot 44 sufficiently to carry the pin 68 toward the left from the position of Fig. 10 to that of Figs. 13 and 14. In so doing, the inclined portion of the slot 66 in the connecting member 64 causes the member 64 and attached segment 58 to be moved forwardly. As soon as the pin 68 has reached the limit of its travel at the end of the slot 66, the handle portion of the arm 40 may be moved rearwardly to adjust the edge gage from the intermediate position of Fig. 6 to the extreme forward position of Fig. 7. In so doing, the connecting member 64 and segment 58 are moved to the positions of Figs. 15 to 17, inclusive, there being no possibility of further movement of the arm 42 about its pivot 44 in this direction.

The locking means for preventing operation of the adjusting arm 40 when the edge gage is moved to its fully retracted position of Fig. 5 comprises the L-shaped slot 70 in the machine frame and is so arranged that, when the pin 68 is in the radial portion of the slot, as in Fig. 10, it is impossible to move the adjusting arm 40. On account of the position of the pin 68 in the radial portion of the slot 70, the pin being guided for movement between the arms 82 projecting from the adjusting shaft 60 in a direction parallel to the radial portion of the slot 70, no movement of the adjusting arm 40 is permitted. To prevent movement of the shifting arm 42 when the edge gage is in its extreme forward position of Fig. 7, the pin 68, being in the outermost portion of the L-shaped slot 70, is retained in this position by said outermost portion. Accordingly, it is impossible to shift the edge gage beyond its intermediate position without causing it to come to rest momentarily. The two arms 40 and 42 are

accordingly manipulated at different times so that there is no possibility of moving the two simultaneously. On account of the limitations in movement of the two handles on the arms 40 and 42, the position of the edge gage may be changed with accuracy to any of its three positions by moving the respective handles as far as possible in each instance, a simple direct movement only being necessary. If desired, the position of the edge gage may be changed merely by shifting the handle of the arm 42 by maintaining a continual grasp on the handle while sewing the heel seat and shank of the shoe and releasing it only along the forepart, so that full control of the shoe may be obtained with both hands supporting the shoe along the forepart to present it properly to the stitch forming devices. However, under extreme conditions it is necessary to support the shoe in the machine as rigidly as possible at all times. Under such conditions it is desirable to employ both hands to support the shoe and to tap the proper handle momentarily as required.

To shift the edge gage from one position to another merely by moving the shifting handle of the arm 42, it is necessary to move the handle bodily with the adjusting arm 40 to shift the edge gage from its extreme forward position of Fig. 7 to its intermediate position of Fig. 6 and to rotate the handle of the arm 42 on its pivot rod 44 to shift the edge gage from its intermediate to its extreme retracted position of Fig. 5. Thus, the attention of the operator need be directed only to a single adjusting handle as heretofore while imparting a shifting movement to the edge gage to a predetermined third fixed position.

In the form of the invention illustrated in Figs. 18 to 20, inclusive, a similar arrangement of edge gage mechanism is provided having two regulating arms 84 and 86, the handle portions of which extend into substantially the same relationship to the machine as in the embodiment of the invention already described, the shifting arm 86 being pivotally mounted on the adjusting arm 84 at 87. In Fig. 18, the edge gage adjusting arm 84 is similar to that in the machine disclosed in United States Letters Patent No. 2,271,611, granted February 3, 1942, upon an application filed in the name of Fred Ashworth and Carl F. Whitaker, more particularly in connection with Figs. 3 and 16 of that patent.

The adjusting arm 84 is a part of a hand-controlled lever fulcrumed on a pivot consisting of a relatively fixed stud screw 88. The lever including the adjusting arm 84, instead of comprising a segmental arm as in the machine of the patent, in this embodiment of the invention, is connected to a rack 90 the teeth of which mesh with a pinion 92 mounted at the lower end of a vertical adjusting shaft 94 the upper end of which carries an adjusting cam 96 engaging the rearward arm of an edge gage in the form of a lever 98 pivotally mounted at 100 on the machine frame.

The connections between the regulating arms 84, 86 and the rack 90 which enable the edge gage to be moved to different positions comprise a slide 104 guided in the machine frame, to which slide the rack 90 is adjustably secured, a pin 106 passing through an inclined cam slot 108 in the slide 104, and a bar 110 slidably mounted in bearings 112 on the arm 84, at the left-hand end of which bar or rod 110, the pin 106 is fixed. The right-hand end of the rod 110 is notched to receive a pivot 114 in a rearwardly extending portion of the arm 86, the arrangement being

such that movement of the adjusting arm 84 causes the slide 104 and rack 90 to be reciprocated and the edge gage to be shifted from extreme forward position to intermediate position. Movement of the arm 86 thereafter causes the edge gage to be shifted from intermediate position to extreme rearward retracted position.

Referring to Fig. 18, the edge gage is illustrated in extreme retracted position, and the arm 86 in forward position. In moving the arm 86 into forward position, the pin 106 is carried to the right inclined end of the slot 108, moving the slide rearwardly. This rearward movement is the result of the camming action between the pin 106 and the inclined end of the slot 108, the pin being guided in a straight path on the rod 110. When the arm 86 is moved rearwardly with relation to the arm 84, the pin 106 occupies a position at the left-hand end of the slot 108 in the slide 104, and the edge gage is shifted to intermediate position as in Fig. 19. Upon movement of the arm 84, the slide and rack are advanced to the extreme forward position, and the edge gage is shifted correspondingly as in Fig. 20.

The means for locking the arms 84 and 86 except for proper sequential movement includes a plate 116 secured to the machine frame by a pair of screws 118. The plate 116 is provided with an L-shaped slot 120 into which the lower end of the pin 106 is guided, the locking action being the same as that described in connection with the L-shaped slot 70 in the construction illustrated in connection with Figs. 1 to 17, inclusive.

With the edge gage adjusting mechanism of the invention, suitable control may be exercised with certainty along all portions of the outseam including that inserted opposite the heel seat of a shoe. Not only is certain and accurate control of the sewing operations obtained by moving the edge gage selectively into any of three positions but the edge gage is maintained along the shank of a shoe in a position which will forestall injury to the inseam with uniformly good results.

In the case of the present machine as illustrated in Fig. 1, the stitch forming devices include a curved hook needle 122, an awl 124, and a shuttle 126. The needle and the awl are actuated to form perforations in the work and to carry loops of thread through the work in the usual way along paths indicated at 128 in Figs. 5 to 7, inclusive. With particular reference to Fig. 6, it will be noted that the sole edge of the shoe is held positively by the edge gage 38 with the inseam 32 at a definite distance from the operating paths of the needle and awl, thus preventing injury to the thread in the inseam so that, in cases of irregularity along the shank of a shoe, particularly where slight displacement occurs in the location of the inseam in the shoe, the edge gage will prevent intersection of the inseam by the stitch forming devices. This result is obtained without impeding the insertion of outsole stitches overlapping the heel seat while the shoe may be guided properly about the forepart and the necessity for complicated and difficult adjustments are avoided. Furthermore, selective shifting of the edge gage into any of three positions may be accomplished through manipulation of a single adjusting device easily operable by one hand with assurance that movement will not be carried through the intermediate position, the parts being locked against such actuation.

The nature and scope of the invention having

been indicated and an embodiment having been specifically described, what is claimed is:

1. An outsole shoe sewing machine having a work support, a needle, an edge gage, and a manually operable arm mounted for limited movement to move the edge gage during sewing operations to either of two positions determined by the limits of arm movement, in combination with means actuatable during sewing operations to shift the edge gage to a third position.
2. An outsole shoe sewing machine having a work support, a needle, an edge gage, and a manually operable arm mounted for limited movement to move the edge gage during sewing operations to either of two positions determined by the limits of arm movement, in combination with means mounted on the arm and operable manually during sewing operations to cause the edge gage to be shifted to a third position other than one determined by the arm at either limit of its movement.
3. An outsole shoe sewing machine having a work support, a needle, an edge gage, and a manually operable arm mounted for limited movement to move the edge gage during sewing operations to either of two positions determined by the limits of arm movement, in combination with a second manually operable arm for shifting the edge gage to a position beyond that determined by the first-mentioned arm at either limit of its movement.
4. An outsole shoe sewing machine having a work support, a needle, an edge gage, and a manually operable arm mounted for limited movement to move the edge gage during sewing operations to either of two positions determined by the limits of arm movement, in combination with a second manually operable arm for shifting the edge gage to a position beyond that determined by the first-mentioned arm at either limit of its movement, and locking means for preventing movement of the first-mentioned arm after the second arm has been operated to shift the edge gage to a position beyond that determined by the first-mentioned arm at either limit of its movement.
5. An outsole shoe sewing machine having a work support, a needle, an edge gage, and a member for moving the edge gage during sewing operations, in combination with manually operable connections for actuating said gage member selectively into any of three predetermined positions, and locking means for preventing continuous movement of said gage member from one position to another without stopping in each position.
6. An outsole shoe sewing machine having a work support, a needle, an edge gage, and a member for moving the edge gage during sewing operations, in combination with two sets of manually operable connections for actuating said member relatively into any of three positions, and locking means acting on said connections to prevent continuous movement of said member through any of said positions.
7. An outsole shoe sewing machine having a work support, a needle, an edge gage, and a member for moving the edge gage during sewing operations, in combination with connections for actuating said member relatively into any of three positions, comprising a manually operable arm, and a pin and cooperating cam slot for actuating the gage member when the arm is operated and for actuating said member independently of the arm when the pin and cam slot

11

are moved relatively to shift the gage while the arm is stationary.

8. An outsole shoe sewing machine having a work support, a needle, an edge gage, and a member for moving the edge gage during sewing operations, in combination with connections for actuating said member relatively into any of three positions, comprising a manually operable arm, a pin and cooperating cam slot for actuating the gage member when the arm is operated and for actuating said member independently of the arm when the pin and cam slot are moved relatively to shift the gage while the arm is stationary, and a second manually operable arm connected to move said pin and cam slot relatively.

9. An outsole shoe sewing machine having a work support, a needle, an edge gage, and a member for moving the edge gage during sewing operations, in combination with connections for actuating said member relatively into any of three positions, comprising a manually operable arm, a pin and cooperating cam slot for actuating the gage member when the arm is operated and for actuating said member independently of the arm when the pin and cam slot are moved relatively to shift the gage while the arm is stationary, a second manually operable arm connected to move said pin and cam slot relatively, and a locking slot for preventing movement of the second arm when the first-mentioned arm is in one position and for preventing movement of the first-mentioned arm when the pin and cam slot are in predetermined relative positions.

10. An outsole shoe sewing machine having a work support, a needle, an edge gage, a rotatable cam member for moving the edge gage during sewing operations, a gear connected to said cam, a segment meshing with the gear, and a manually operable arm mounted for limited movement and rotatable concentrically with the segment for actuating the segment to move the edge gage to either of two positions determined by the limits of arm movement, in combination with means for connecting the arm and segment, comprising a pin and cam slot relatively movable to cause the

12

edge gage to be shifted to a third position while the arm remains stationary.

11. An outsole shoe sewing machine having a work support, a needle, an edge gage, a rotatable cam member for moving the edge gage during sewing operations, a gear connected to said cam, a segment meshing with the gear, and a manually operable arm mounted for limited movement and rotatable concentrically with the segment for actuating the segment to move the edge gage to either of two positions determined by the limits of arm movement, in combination with means for connecting the arm and segment, comprising a pin and cam slot relatively movable to cause the edge gage to be shifted to a third position while the arm remains stationary, and a relatively stationary part of the machine having an L-shaped slot to lock the pin against relative movement with the cam slot when the arm is operated to one limit of its movement and to lock the arm when the pin is moved to shift the edge gage to said third position.

12. An outsole shoe sewing machine having a work support, a needle, an edge gage, a rotatable cam member for moving the edge gage during sewing operations, a gear connected to said cam, a rack meshing with the gear, a slide member to which the rack is secured, and a manually operable arm mounted for limited movement to move the edge gage to either of two positions determined by the limits of arm movement, in combination with means for connecting the arm and slide, comprising a pin and cam slot relatively movable to cause the edge gage to be shifted to a third position while the arm remains stationary, and a second arm for moving the pin relatively to the cam slot.
